United States Patent Office

Des. 184,505
Patented Mar. 3, 1959

184,505

BRACELET

Joseph A. Bobley, Rye, N. Y.

Application July 10, 1958, Serial No. 51,727

Term of patent 3½ years

(Cl. D45—4)

I claim:

The ornamental design for a bracelet, substantially as shown.
